MULTIPLE EFFECT EVAPORATOR

Hugh K. Moore, Berlin, N. H., assignor to Brown Company, Berlin, N. H., a corporation of Maine

Application January 5, 1932, Serial No. 584,823

21 Claims. (Cl. 159—17)

This invention relates to apparatus for evaporating water efficiently from dilute liquors initially containing a large proportion of water. While the principles of the apparatus herein described are generally applicable to the evaporation of aqueous liquors, the evaporator is more especially designed for the efficient evaporation of water from liquors such as the black liquor from the sulphate process of digesting wood chips, such liquor becoming viscous and tacky when a considerable proportion of the water is removed therefrom. The present invention relates more especially to the evaporation of water from liquors containing substances which are liable to cause troublesome scale within the evaporator, this being true of the black liquor from the sulphate process. The multiple effect evaporator herein described is in general similar to that described and illustrated in my Patent No. 1,582,067, but includes a number of improved features which have been incorporated for the purpose of overcoming certain difficulties which have been experienced in the operation of ten-effect evaporators in the evaporation of black liquor from sulphate cooks.

The black liquor which is discharged from a digester after a sulphate cook contains a large number of substances including various lignin compounds and the sulphates and carbonates of sodium and calcium. The primary purpose of the evaporator is to concentrate the black liquor by removal of as much as possible of its aqueous content so that the lignin compounds which include roughly 43 per cent of inorganic matter and 57 per cent of organic matter can be calcined with the addition of salt cake to produce soda ash and sodium sulphide. The former is subsequently causticized by the addition of lime to form caustic soda. It is desirable that as much as possible of the salt cake be reduced to sodium sulphide in the furnace according to the equation

this being an endothermic reaction depending on the temperature for its degree of completion. Hence it is desirable that the temperature of the furnace be as high as possible. The temperature of the furnace, in turn, depends on the concentration of the black liquor supplied thereto, since the more heat required for the evaporation of the remaining aqueous content of the concentrated black liquor, the less heat will be left from the combustion of the liquor to promote the reduction of the salt cake. For this reason, the degree of concentration of the black liquor delivered

from the evaporator to the furnace determines in large measure the efficiency of the entire cycle of operations constituting what is known as the sulphate process of pulp digestion. It is an object of the present invention to provide apparatus which is capable of concentrating black liquor to a considerably higher degree than has heretofore been practically possible, this being accomplished according to the present invention with less clogging of the evaporator than has heretofore been encountered in the operation of evaporators of this type. Moreover, according to the present invention, various additional economies are effected as hereinafter more fully set forth.

Multiple effect evaporators consist of a number of separate units or effects which operate in a series of descending temperatures and pressures. Steam at maximum pressure is introduced into the end effect usually designated as #1 to boil liquor contained in this effect. The steam boiled out from the liquor is carried to #2 effect at a lower temperature and pressure to boil liquor therein which is at a still lower temperature. The steam generated from the liquor in #2 effect is passed to #3 effect, and so on, down the line until the steam from #10 effect (in a ten-effect evaporator) is carried off to a condenser in which is preferably maintained a high vacuum in order that the boiling point in the last effect may be as low as possible. The course of the liquor through the evaporator may be from #1 through the successively cooler effects to #10. In such case, it is advisable that the liquor be at a temperature as nearly as possible to the temperature of the liquor in the effect to which it is to be pumped, else a great deal of the steam supplied to #1 is wasted in raising the liquor therein to the boiling point. As the liquor progresses from one effect to the next, it increases in density and decreases in temperature until it is discharged from #10 effect at a relatively low temperature and maximum density. Since black liquor when concentrated is thick and tacky at the usual operating temperature of #10 effect, the degree of concentration to which the liquor may be evaporated in this way is greatly limited. Instead of sending the liquor through the effects in succession from #1 to #10, the direction of flow of the liquor may be reversed, the weak liquor being introduced into #10 effect and progressing successively through the effects to #1. This has the advantage of delivering the concentrated liquor at the temperature of the hottest effect so that a far greater degree of concentration is possible owing to the reduced viscosity of the concentrated liquor in its heated

condition. The weak liquor which is supplied to the evaporator is, however, ordinarily at a fairly high temperature, considerably above that of #10 effect. Hence if hot liquor is sent through the evaporator in reverse direction, that is, from #10 through the successive effects to #1, a great deal of this initial heat is lost when the liquor enters #10 effect. As set forth in my Patent No. 1,582,-067, I prefer to introduce the weak liquor into an intermediate effect, as for example, #5. From this effect, it is sent through progressively cooler effects, #6, #7, #8, #9, and #10. The liquor from #10 is then sent through progressively hotter effects, #4, #3, #2 and #1. Since the temperature of #4 is considerably higher than #10, it is necessary for the sake of economy to heat the liquor from #10 materially before introducing it into #4. To this end, the hot weak liquor from the storage tank is brought into heat-exchanging relationship with the cold, partially concentrated liquor from #10 effect before it is introduced into the evaporator so that the excess heat in the weak liquor is utilized to raise the temperature of the cold liquor from #10, this partial cooling of the initially hot liquor supplied from the storage tank being additionally desirable since it reduces the temperature to a point suitable for economical introduction into #5 effect. The incidental advantages arising from this manner of circulating the liquor through the evaporator are discussed in full in my patent hereinbefore referred to.

When the liquor progressing through a ten-effect evaporator reaches the last two or three stages of evaporation, it becomes increasingly difficult to handle due to its physical characteristics arising from the high concentration of solids therein. Black liquor contains a certain amount of calcium sulphate which, in the weak liquor, is largely, if not wholly, in solution. As the liquor becomes more concentrated, an increasing amount of calcium sulphate is forced out of solution. The precipitate at first takes the hydrated form of $\text{CaSO}_4 \cdot 2\text{H}_2\text{O}$. This is a soft compound and is not of itself troublesome. However, if exposed to heated surfaces such as the tubes in the hotter effects through which the liquor passes, the soft hydrated form of the calcium sulphate loses its water of hydration and changes to anhydrous calcium sulphate, as follows:

This anhydrous form of the sulphate, known as anhydrite, is a hard glassy mineral. When a substantial layer of this mineral is formed on the inner surface of evaporator tubes, its low heat-conducting properties greatly reduce the efficiency of the evaporator and the effective diameter of the tubes so that it is necessary from time to time to remove this scale from the tubes. In the salt-making industry, such scale is frequently encountered on the exterior surfaces of the evaporator pipes. It can be removed in such cases by being broken up with a sledge hammer. When the scale forms on the interior surface of tubes, the problem of its removal is far more difficult. Various methods of removal have been tried such as rotating burrs to bore the scale out of the tube. This is extremely difficult owing to the glass-like hardness of the anhydrite, the burr being as liable to injure the tube itself as to cut out the scale. A method which has been somewhat successful has been to surround the tubes with cold water, then to introduce an oxy-acetylene flame within the tubes to crack up the scale, the tubes themselves being protected by the cold water. While

this method works well with pure anhydrite, it is not so successful with anhydrite deposited from black liquor. This is due to the presence of a considerable quantity of extremely fine fiber material from the pulp, this material being so fine that it is practically impossible to remove it from the black liquor. Cellulosic fibers are slightly denser than water and therefore tend to settle. The effective density of the fine fibrous material in the black liquor when it reaches a fairly concentrated stage, is greatly increased by the fact that owing to the concentration of the liquor, an increasing amount of sodium sulphate is forced out of solution, the minute crystals of this sulphate attaching themselves to the fibers. This causes the settling of the fibrous material in horizontal evaporator tubes so that as anhydrite scale is formed, a considerable amount of fiber is caught therein. This makes the scale tougher and less brittle. The presence of the fiber also practically prevents washing of the scale from the tubes, in spite of the ready solubility of the sodium sulphate. When wash water is sent through the tubes, the first layer of mineral washed from the surface of the scale exposes a fuzz of fiber which acts as a blanket to prevent effective access of wash water to the remaining scale. According to the present invention, these difficulties are avoided and the efficiency of the evaporator as a whole is increased by providing means for preventing the formation of scale on the inner surfaces of the tubes. This is accomplished according to the invention by constructing effects #1 and #2 with vertical evaporator tubes instead of horizontal as in the other effects and by providing continuously operating scrapers to keep the walls of these tubes clear. For satisfactory operation of such mechanism, it is necessary that the scrapers be arranged in such a manner as to be easily accessible for replacement or repair and that they be of such size and shape as not to interfere with the circulation of liquor in the effect. Furthermore, the structure should be such as to ensure the efficient removal from the scraper of the solids which are scraped from the surfaces of the tubes. The use of vertical tube effects for the last two stages of evaporation is advantageous in that such structure lends itself more conveniently to the use of reciprocating scrapers within the tubes, and thus there is less tendency on the part of the fibrous material which is laden with sodium sulphate crystals to settle out against the wall of the tubes. By the use of scraping devices such as are hereinafter more particularly described, not only is it possible to deliver the concentrated black liquor at a considerably higher degree of concentration than has heretofore been possible, but the evaporator as a whole can be run for longer periods between washings.

The invention also includes various improved features of structure which combine to make possible the operation of an evaporator of this type at a much higher efficiency than has been heretofore possible. In the horizontal effects, it is necessary for maximum efficiency to keep the entire area of the inner surfaces of the tubes wet at all times with liquor. In the effects through which the relatively weak liquor is passed, the volume of such liquor is ordinarily sufficient of itself to keep the tubes full of liquor and its foam. As the liquor becomes more and more concentrated after successive steps of evaporation, the stream eventually is not sufficient to wet the entire inner surface of the tubes. For this reason, I have heretofore re-circulated a portion of the

5 Liquor passing through each effect so as to augment the size of the stream actually passing through the tubes and thus to keep the tubes sufficiently full. This, however, is objectionable
 10 since the re-circulated liquor is more concentrated than the liquor entering the effect so that the boiling point is altered and the efficiency of the effect is somewhat decreased. According to the present invention, I provide dams outside of
 15 the discharge ends of the tubes so that a certain amount of liquor can back up in the tubes to fill the same sufficiently without necessitating a re-circulation of a portion of the liquor therein.

20 In the operation of a multiple effect evaporator, pumps are essential for the circulation of the liquor through the successive effects. Since the liquor from each effect is discharged therefrom immediately after having been boiled by the steam surrounding the tubes through which it has passed, the liquor from each effect thus reaches the corresponding pump at a temperature very close to the boiling point corresponding to its pressure. No pump works at 100% efficiency; that is, in the operation of a pump of
 25 any kind, a certain amount of the energy exerted in driving the pump is wasted in generating heat. In the centrifugal pumps which have been found to be the most efficient types for pumping the liquor from one effect to another, about 50% of
 30 the energy input is thus converted into heat. This heat raises the temperature of the incoming liquor so that the latter boils sufficiently to fill the pump with steam. This renders the pump ineffective. The expedient of placing the pumps
 35 at the bottom of deep pits about thirty feet below the effects has been tried with more or less success. When in the pits, however, the pumps usually fail to receive the attention and care which they require. According to the present invention, the steam within each pump is condensed so as to permit the pump to operate effectively. It is impracticable to attempt to cool the pump itself from the outside. It is likewise undesirable to inject cold water into the pumps since
 40 the water thus introduced will have to be evaporated. According to the invention, I introduce into each pump cold liquor from #10 evaporator. This liquor, although partially concentrated, contains a considerable percentage of water, but as
 45 this water has to be evaporated anyway, no loss of efficiency results from its introduction into the several pumps. Special structure by which the cold liquor is introduced into the pumps efficiently, is hereinafter described.

50 55 In a multiple effect evaporator having horizontal effects, it is advantageous to distribute the liquor in each effect as evenly as possible among the evaporating tubes therein. To this end, as shown in my Patent No. 1,582,066, I may provide nozzles in the several effects particularly designed to distribute the liquor passing therethrough among the several tubes in each effect in such a manner that the liquor is divided evenly among the tubes. The nozzle in each effect is assisted
 55 by the use of gill flanges which extend across the tube sheet immediately below each horizontal row of tubes, and serve to equalize the flow through the tubes in each row. The nozzles described and illustrated in the patents referred to to operate on the principle of combining a straight jet or core of liquor with a whirling conical stream. The conical stream impinges on the jet at the orifice of the nozzle where it breaks up and is broken up by the jet into a cone of spray affording a substantially uniform distribution of the total stream

60 over the area of the tube plate. It has been found in practice that nozzles of this type work satisfactorily up to a $\frac{3}{8}$ " outlet. It seems impossible to make nozzles larger than $\frac{3}{8}$ " that will either have the required angle of discharge or that will give a uniform spray under varying pressures. The reason for this is that the volume of the jet or core of the stream varies as the square of the diameter, while the surface of the core varies only as the diameter. Thus at high velocities the 65 centrifugal or ripping action of the liquor outside of the core affects only the surface of the core and is not transferred to the interior of the core. At lower velocities, the core is not disrupted and the core of liquor goes through as a straight stream. On the other hand, at higher pressures, the core will be disrupted to such an extent that you will obtain a hollow cone which is the very thing to avoid as it does not get equal distribution over the tubes. In other words, a 70 large nozzle is capable of furnishing a suitable cone of spray only at a given pressure. Slight variations either above or below such pressure result either in a spray with a solid stream in the center and vacant spaces around it, or in a hollow cone with no stream in the center. It is a practical impossibility to supply liquor to the several effects at anything like uniform pressures. Hence the nozzle must be capable of efficient distribution over a considerable range of pressures. 75 It is also desirable that nozzles be capable of operating properly with liquors of different viscosities. In order to fulfill these conditions, it is necessary to use small sized nozzles. If a single nozzle is incapable of taking care of the entire stream 80 of incoming liquor, I may provide a plurality of nozzles distributed in such a manner as to cooperate in the uniform distribution of liquor to the tubes. While the distribution of the liquor by a plurality of nozzles may not be theoretically 85 as uniform as a single nozzle, the gill flanges assist in attaining reasonable uniformity of distribution. There is one characteristic of small nozzles which has to be considered, namely, the fact that due to resistance in the nozzles themselves, an increase in pressure in the liquor supplied thereto does not result in a corresponding increase in the volume of liquor passing through the nozzle. In fact, the point can be reached where very little increase in volume may be obtained for a tremendous increase in pressure. It sometimes happens in mill operation that for some reason connected with other parts of a plant, the capacity of the evaporator has to be increased suddenly. This can be done either by 90 increasing in size of the nozzles or increasing the number of nozzles in each effect. It is out of the question as a practical matter to change the size of the nozzles since that would mean cooling the entire evaporator so as to permit access 95 to the interior of each effect for the replacement of the nozzles by larger or smaller ones. Consequently, according to the present invention, two or more separate batteries of nozzles are installed in each effect, each battery consisting of 100 a set of nozzles arranged to provide substantially uniform distribution independently of the other set or sets of nozzles within the effect. Hence, by opening or closing a valve outside of an effect, an additional battery of nozzles can be put into 105 operation or shut off to increase or decrease the capacity of the effect, as the case may be. Where a plurality of nozzles are assembled in a battery of this kind, it is desirable that the lower nozzles be somewhat smaller than the upper noz- 110

zles to compensate for the greater pressure of the liquid entering the lower nozzles due to static head.

As set forth in my Patent No. 1,582,067, it is desirable to employ a heat exchanger for the purpose of using some of the heat in the hot weak liquor supplied to the evaporator to raise the temperature of the cold, partially concentrated liquor, which is pumped from effect #10 to one of the intermediate effects for further concentration. For an efficient heat exchange, I employ a vertical exchanger sixty feet high in which the liquor to be cooled is entered at the top and flows to the bottom, the liquor to be heated entering at the bottom and flowing out at the top. While it is conceivable that a sixty-foot exchanger might be constructed with pipes in single sections of that length, it is better to construct the exchanger in sections having pipes not over twenty feet in length. According to the invention, a heat exchanger is provided, as hereinafter described, in which three twenty-foot sections are joined together in such a manner as to form a substantially unitary sixty-foot exchanger, the design being such as to promote efficient circulation of one stream of liquor through the tubes and the other stream of liquor in the space around and between the tubes, and to minimize the possibility of clogging.

Owing to any one of a number of causes, such as variations in steam pressure supplied to the evaporator, variation in the concentration or temperature of the weak liquor supplied from the storage tank, or variation in the voltage supplied to the motors which drive the circulating pumps used for the evaporator, the apparatus as a whole must as a practical matter work under the conditions which vary from time to time. It therefore becomes necessary to regulate the rate of delivery of liquor from one effect to the next in such a manner that undue accumulation, or the reverse, in any particular effect is avoided. For changes of considerable magnitude in the size of the liquor streams delivered from each effect to the next succeeding effect such as would result from a considerable change in the rate of supply of weak liquor to the evaporator, hand-operable gate valves are supplied in the liquor lines connecting the several successive effects. The volume of the liquor streams are, however, subject to small incidental variations for various causes. In order to take care of such minor fluctuations, I provide automatic control means for regulating the rate of discharge of liquor from each effect to the next. To this end, I provide a by-pass around each delivery pump, this by-pass having therein an automatic valve adapted to modify the effective delivery rate of the pump, as hereinafter described in detail.

The primary purpose of the entire evaporating apparatus is to recover the chemicals present in the weak liquor and to remove by evaporation the water in which the chemicals are carried in solution or otherwise. Hence it is desirable that the condensate from the several effects and from the main condenser to which the steam from #10 effect is delivered, should be pure water. In order to provide means for keeping track of the action of the evaporator in this respect, I provide a weir, as hereinafter described, which is designed not only to measure the quantity of steam delivered from the evaporator but also to indicate visually the purity of the condensate. This is accomplished by means of a suitably placed sight glass mounted on the side of the weir in

such a manner that a portion of the stream of condensate flows therethrough so that if the condensate is contaminated by any liquor, it is colored thereby and the result is clearly visible. This feature is of practical importance in mill practice since the average operator works by rule of thumb more than from actual knowledge of what is going on inside of the apparatus. Suppose, for example, the operator is told to carry 28 inches vacuum. If the barometer reads 29 10 inches, the condenser will be operated at one inch absolute pressure, but if the barometer stands at 30 inches, the condenser will be operating at two inches absolute pressure. The volume of one pound of steam at one inch absolute 15 is nearly twice the volume of the same quantity of steam at two inches absolute, so that the velocity of the stream of steam flowing from #10 effect to the condenser is proportionately greater when the apparatus is operated to maintain only one 20 inch absolute pressure in the condenser than it is when the apparatus is operated to maintain two inches absolute pressure. As the condenser pressure affects the pressures in the several effects, a decrease in condenser pressure means increased velocity of the steam discharged from the effects all along the line. This increased velocity due to the lowered pressure may result in the entraining of droplets of liquor in the swiftly flowing streams of steam. If liquor is 30 thus carried into the next effect or into the condenser, it discolors the condensate delivered to the weir and hence acts as a warning to the operator to reduce the vacuum. Although reduction of vacuum in the condenser is an effective 35 way of preventing escape of liquor with the condensate, it is undesirable as a permanent remedy as it lowers the thermal efficiency of the evaporator as a whole. If trouble is had with entrainment of liquor in the steam, it is better to enlarge 40 the steam pipes from the effects in order to reduce the velocity of the steam. Furthermore, according to the present invention, I provide structure within each effect designed for more efficient separation of liquor from the steam before 45 the latter leaves the effect. This reduces the minimum sizes of the steam discharge pipes consistent with a clear condensate and a low pressure in the condenser. Such structure is hereinafter described.

In handling the condensate from different effects, float valves have been used to regulate the rate at which the water was sucked from one effect to the next by the pressure drops between the effects. These floats operate valves which 55 let the water go through, but which prevent the steam from passing from one effect to the next. In washing out the evaporator, a fine mud-like pulp tended to collect in these valves so that occasionally the plant would have to be shut down 60 in order to clean out the valves since the accumulation of sediment hindered the valves from closing properly. According to the present invention, I provide traps in the form of wells which are sufficiently deep to require no valves 65 therein. In the apparatus hereinafter described, the pressure differences between most of the effects are so small that a well having a depth of eight to ten feet is sufficient to prevent the steam from one effect blowing over into the next through 70 the trap. In the first two effects, however, the differences of steam pressure are considerably greater so that regulating valves are employed between the first three effects instead of the wells. For this purpose, I employ butterfly valves which 75

are less liable to clog than the balanced valves previously used.

At the end of a pulp cook, there is a large amount of steam ordinarily lost when the charge of pulp and liquor is blown off from the digester into the blow pits. This steam represents a serious loss and waste of heat. According to the invention, I provide means for saving a great deal of this heat in connection with the operation of the evaporator. For the efficient operation of the evaporator as described, it is advantageous to introduce the weak liquor at a comparatively high temperature. Thus the weak liquor in the storage tank should be maintained as hot as possible. In order to keep up or to raise the temperature of the liquor in the storage tank, I may provide a condenser of suitable size adjacent to the tank, the condenser being connected with the tank itself at different levels. Into this condenser, I discharge any waste steam which may be available from any part of the mill, especially from the blow pits. These intermittent discharges of steam are thus utilized to heat the liquor which is allowed to circulate from the storage tank through the condenser. This results in a considerable economy in the operation of a mill.

For a more complete understanding of the invention, reference may be had to the description which follows, and to the drawings, of which:—

Figures 1-3 illustrate a ten-effect evaporator containing the improvements embodying the present invention. These ten effects are indicated as #1, #2, #10, #1 and #2 being as shown as vertical effects, #3 to #10 being shown as horizontal effects. It is evident that the invention may be embodied in multiple effect evaporators consisting of different numbers of vertical effects, of horizontal effects, and differing in the total number of effects. The vertical and horizontal effects are more fully illustrated in Figures 4 and 9 respectively, and are hereinafter more fully described. In many respects, the evaporator herein illustrated resembles that described and illustrated in my Patents Nos. 1,582,066 and 1,582,067. As shown, the effects are arranged in order of descending pressures and temperatures, effect #1 having the highest temperature and pressure therein.

The apparatus illustrated on the drawings is designed for operation by steam, high pressure steam being supplied initially through a pipe 30 to the steam chamber of effect #1. Each of the effects herein described consists of a boiler shell, the interior of which is divided into three chambers by transverse tube sheets, as hereinafter more fully described. The intermediate chamber is the steam chamber, a number of tubes being mounted in the tube sheets to extend through the steam chamber and to open into the two end chambers. These tubes carry the liquor to be evaporated, the liquor being heated by the steam in the steam chamber. The liquor in the tubes is boiled as it passes therethrough so that a mixture of steam and unevaporated liquor is discharged into one of the end chambers. The steam is separated from the liquor and is carried over into the steam chamber of the next successive evaporator which operates at a lower temperature. This steam heats and boils the liquor passing through the tubes of this evaporator so as to form steam for operating the next successive evaporator in a manner well known in the art of multiple effect evaporation. As shown in Figures 1 and 2, the steam separated from the boiling liquor in #1 effect is sent through a steam pipe 31 to the steam chamber of effect #2. The steam from #2 effect is sent through a steam pipe 32 to #3 effect. In like manner, the steam from effect #3 is sent through a steam pipe 33 to the steam chamber of effect #4, and so on down the line until the steam from #10 effect is discharged through a steam pipe 34 to a condenser 35, diagrammatically indicated in Figure 3. The steam lines to the successive horizontal effects may be mechanically joined together to form an apparently continuous pipe for the purpose of simplifying the support thereof. This pipe is blanked off as at 36 between the supply line and end discharge line of each effect. If, for any reason, it is desired to cut out an effect entirely from the apparatus, the corresponding blanking plate may be removed so as to by-pass the steam past the effect thus cut out. In heating the liquor in any of the effects, the steam which enters the effect is for the most part condensed so that a consider-

able amount of condensate is formed in each effect, the temperature of such condensate depending on the effect in which it is formed. In order to utilize the heat in the condensate formed in the hotter effects, the condensate from each effect is sent successively to the steam chambers of the remainder of the effects so that the excess heat therein flashes off into steam in the successive steam chambers owing to the progressively lower pressures therein, which helps to heat the liquor passing through the tubes. Thus the condensate formed in #1 effect flows off through a pipe 40 to #2 effect, this flow being controlled by a suitable valve 41 as hereinafter explained in more detail. In like manner, the condensate from effect #2 flows off through a pipe 42 controlled by a similar valve 43, and is introduced into the steam chamber of effect #3. The condensate piping system is illustrated more clearly in Figure 3. As shown, the pipe 42 extends continuously past all the horizontal effects to a weir 44, and thence downwardly to a water-seal 45 which is located thirty feet or more below the pipe 42 so that discharge may be accomplished at all times therethrough at low pressures in the steam chamber of #10 effect without sucking air. At each effect a normally closed valve 46 is in the pipe line 42. On the supply side of each valve 46 a branch pipe 47 leads into the steam chamber of the corresponding effect, or, as shown, into the upper end of a well 48 which is mounted below the steam chamber of each effect to catch the condensate flowing therefrom. The bottom of each well is connected as by a pipe 49 to the other side of the corresponding valve 46 so that when all the valves 46 are in their normally closed position, the condensate flows upwardly through the branch pipes 47 and back through the wells 48 and connecting pipes 49 to the next section of the pipe 42. The pipes 47 and 49 may be supplied with suitable normally open gate valves 50 and 51. If it is desired to cut out any single effect from the series, the corresponding valves 50 and 51 may be closed and the corresponding valve 46 opened so as to by-pass the condensate. The condensate from the condenser 35 is preferably sent through a weir 52 and down to a water-seal or trap 53 located thirty feet or more below the condenser.

Figure 3 also illustrates the piping system for removal of adventitious air or other gases which may be carried into the effects with the steam supply. It is practically impossible to supply steam which is wholly free from air or other gases. If such gases are allowed to collect in the effects, their pressure soon increases until it seriously affects the operation of the effects, the efficiency of which operation depends in large measure upon the pressures maintained therein. Hence, an exhaust pipe 55 is connected to the upper portion of the steam chamber in #1 effect and leads to the upper portion of the steam chamber in #2 effect. From this steam chamber, a pipe 56 extends past all the horizontal effects to the condenser 35. From the condenser a pipe 57 leads to a suitable vacuum pump, not shown. At each horizontal effect, the pipe 56 is stopped by a normally closed gate valve 60. On either side of these gate valves are pipes 61 and 62 leading from the pipe 56 to the upper portions of the steam chambers in the several effects. The air from #2 effect, together with a certain amount of entrained steam, enters the steam chamber of #3 effect through the pipe 61

and leaves this effect through the pipe 62. From this effect, it enters and leaves each of the succeeding effects until it is finally drawn through the condenser 35 to the vacuum pump. Gate valves 63 and 64 may be connected respectively in the pipes 61 and 62 for each effect so that if it is desired to cut out an effect, these valves may be closed and the corresponding valve 60 opened to by-pass the flow.

The weak liquor which is supplied to the evaporator is preferably sent first to one of the intermediate effects and thence through successively colder effects to effect #10, from which it is sent through the remaining hotter effects in order of increasing temperature until it is finally discharged from effect #1, as described in my Patent No. 1,582,067. As shown on the drawings by way of illustration, the weak liquor is initially entered in #5 effect, but it is apparent that it may be entered first in any of the other effects, as desired. As shown in Figures 1 and 2, the weak liquor may be supplied from a storage tank 70 through a supply line 71 which may be connected with the tank 70 both by a branch line 72 entering the tank at an intermediate point between its top and bottom and by another branch 73 entering the bottom of the tank. Suitable gate valves 74 and 75 may be supplied for controlling these branch pipes. The pipe 71, carrying hot weak liquor from the tank 70, is connected to the suction end of a suitable pump 80 which discharges through a pipe 81 into one of the intermediate effects, such as for example, effect #5. This particular supply pipe 81 passes through a heat exchanger 82 as illustrated in Figure 1, for a purpose explained in my Patent No. 1,582,067 and hereinafter set forth. Each effect is provided with a supply pump 80 from which liquor is pumped into the effect through a supply pipe 81. The unevaporated liquor from #5 effect is pumped into #6 effect. In like manner, the unevaporated liquor from each of the next succeeding cooler effects is pumped from one effect to the next until the coldest effect #10 is reached. The partially concentrated liquor from this effect is sent through a pipe 85 to a pump 86 from which it is discharged for the most part into a pipe 87 leading to the heat exchanger 82. This cold liquor, in passing through the heat exchanger 82, receives considerable heat from the hot weak liquor supplied from the tank 70 so that as it emerges from the exchanger 82 through a pipe 88, its temperature has been considerably raised. Since the pipe 88 leads to effect #4, the higher temperature of the liquor in this pipe, the less steam will be required in this effect to raise the liquor therein to its boiling point. From the well 84 of #4 effect, the unevaporated portion of the liquor is discharged through a pump 88 to #3 effect and thence to the upper chamber of #2 effect. From this effect, the unevaporated liquor is drawn off from the lower chamber and is sent through a pump 80 to the upper chamber in #1 effect. The concentrated liquor from #1 effect is finally discharged through a pump 80 and a pipe 88 to the furnace (not shown).

For the proper operation of the evaporator as a whole, it is necessary that the flow of liquor through each individual effect be carefully regulated so that there will be sufficient liquor supplied to each effect, but not too much. In order to regulate such supply, a gate valve 90 is mounted in the suction line of each pump 80, these

valves being operated by hand to adjust the evaporator as a whole to any particular condition of operation. In addition to this regulation which takes care of sizeable changes in the rate 5 of supply of weak liquor to the evaporator and the temperature of such liquor, I provide automatic means for taking care of small variations which occur constantly during the operation of the evaporator and which arise from any one 10 or more of a considerable number of causes. To this end, each of the pumps 80 is provided with a by-pass 91 through which liquor discharged from any of the pumps 80 may be re-circulated directly back to the suction of the same pump. In 15 each by-pass 91 is a control valve 92, preferably of the butterfly type, as illustrated in Figure 23. The valves 92 are each automatically regulated in accordance with the level of the liquor in the well 84 of the effect to which the liquor is being 20 pumped. Thus the rate of supply of liquor to any effect is controlled within a limited range by the liquid level in the discharge well of the same effect. Hence, if any one of the effects varies in its efficiency so as to evaporate a greater 25 or less percentage of the liquor supplied thereto so that the rate of supply changes, this change in the rate of supply affects each of the other effects, the supply streams to these other effects being individually regulated by respective valves 30 92, which in turn may be controlled by apparatus such as is illustrated in Figure 22. As therein shown, a float tank 93 may be mounted alongside of each well 84, the tank being in communication with the well through a pair of connecting 35 pipes 94 near the top and bottom thereof. Within the tank is a float 95 of suitable size to which is attached an endless chain 96 passing over a pair of sprocket wheels 97, 98. The lower sprocket wheel 98 is mounted on a shaft which 40 projects through the casing of the float tank 93 and which carries an external sprocket wheel 100. The latter is connected as by a suitable chain 101 to a larger sprocket wheel 102 mounted on a shaft 103, the butterfly member 104 of the 45 valve 92 being also mounted on the shaft 103. Since the liquid level in the float tank 93 is always equal to that in the well 84, changes of level in the well will result in a rise or fall of the float 50 95 between suitable limit stops 105 and 106. This motion of the float rotates the external sprocket wheel 100, which in turn turns the sprocket wheel 102 through the chain connection 101 and thus varies the angular position of the butterfly member 104. If, for example, one of 55 the pumps 80 slows down so that it does not draw the unevaporated liquor from the corresponding well 84 of an effect as fast as it is being discharged into the well from that effect, the liquor will accumulate in the well, causing a rise of 60 level therein. The corresponding rise of level in the float tank 93 raises the float 95 and thus rotates the sprocket wheel 102 through a proportional angle to open the valve 92 wider than it was before. This permits the re-circulation 65 of a larger proportion of the liquor discharged from the pump 80 which supplies the effect referred to, through its by-pass 91, with a correspondingly lesser proportion of liquor passing through the supply pipe 81 into the effect. 70 Hence, the supply stream of liquor to the effect is reduced until the supply balances the previously diminished discharge stream from the well 84. By means of these by-passes for recirculating a portion of the liquor discharged from each 75 pump 80, undesirable back pressures on the

pumps are avoided. The butterfly type of valve is especially desirable in this connection since it is less liable to become clogged by accumulations of fiber, scale, etc., than are other types of valves.

Owing to the decreasing pressures in the successive effects from #1 to #10, it is not necessary to pump the condensate formed in the several effects from one to the next, the higher pressures in the hotter effects being sufficient to force the condensate into the next successive effects. Where the difference of pressure between successive effects is moderate, I do away with control valves in the condensate pipe line by installing wells 48 of sufficient depth to serve as traps beneath the steam chamber of each such effect. In the operation of a ten-effect evaporator such as is illustrated on the drawings, the pressure differences between successive horizontal effects are relatively small so that the wells 48 need not be excessively deep to provide sufficient liquid head to prevent the pressure in these effects from blowing steam through the condensate pipes to the next effects. On the contrary, the head of condensate in the pipes 47 will maintain a liquid level in the well 48 of the preceding effect. In the embodiment of the invention illustrated on the drawings, the vertical effects #1 and #2 have far less total tube surface than the horizontal effects. Hence, in order to keep in step with effects #3 to #10, the pressure differences between effects #1 and #2 and between effects #2 and #3 must be considerably greater than the pressure differences between successive horizontal effects. For this reason, it is impracticable to attempt to provide wells sufficiently deep between effects #2 and #3 of sufficient depth to act as steam traps between these effects. Instead I prefer to provide regulating valves 41 and 43, as shown in Figure 3. These valves are preferably of a non-clogging type such as the butterfly valve illustrated in Figure 23. For the control of these valves, I may provide float tanks 110 which may be identical in structure and associated mechanism with the float tanks 93 illustrated in Figure 22 and hereinbefore described for the regulation of by-pass streams in the liquor supply lines.

In concentrating sulphate liquor by evaporation, the liquor eventually reaches a thick viscous consistency which renders it exceedingly difficult to handle. When the liquor has been concentrated to a point at which 60% or more thereof is solid material, it is so viscous that when cold it is an extremely tacky or gummy solid. Hence, in order to pump such liquor through pipes, it must be handled at relatively high temperatures. For this reason, the liquor entering the evaporator is routed first through the colder effects for partial concentration, then through successively hotter effects until it is finally discharged from the hottest end of the evaporator. Sulphate pulp liquors contain calcium salts which as a rule are more soluble in cold water than in hot water so that there is an increasing tendency on the part of the liquor as it becomes more concentrated and hotter, to force the calcium salts out of solution, both by reason of the increased concentration and the increased temperature. As sulphate liquors usually contain harmful percentages of calcium sulphate, in the concentrated hot liquor an increasing quantity of such salt is forced out of solution into its solid form. When first precipitated from the solution, this salt is usually in its

hydrated form ($\text{CaSO}_4 \cdot 2\text{H}_2\text{O}$) which is soft solid. If this hydrated form of the salt is strongly heated, as by proximity to the heated surfaces of the evaporating tubes in the hotter effects, the water 5 of hydration is driven off with the formation of anhydrous calcium sulphate, known as anhydrite, a hard glassy substance which is exceedingly difficult to remove when it forms as scale on the interior surfaces of heated pipes. According to 10 the present invention, I provide mechanism by which the formation of anhydrite is forestalled by scraping the hydrous calcium sulphate from the surfaces of the tubes in the hotter effects before it has a chance to change into the anhydrous form. To this end, I may employ in the 15 hottest effect or effects, such as #1 and #2 effects, scraping apparatus such as is illustrated in Figures 4-8. The effects in which scrapers are used are preferably of the vertical type, each consisting of a vertical shell 115 in which are mounted 20 a pair of tube sheets 116 and 117 which divide the effect into three chambers, an upper chamber 118, an intermediate steam chamber 119, and a lower chamber 120. A plurality of tubes 121 extend through the steam chamber 119 from one tube sheet to the other and open into the end chambers 118 and 120 respectively. There is also provided a central passage of large diameter connecting the end chambers. As shown, this 25 passage extends through a corrugated pipe section 122, the ends of which are secured to the tube sheets 116 and 117, the pipe being corrugated to take care of thermal expansion. In order to avoid wear on the inner surfaces of the pipe by friction of solids carried by the liquor against the corrugation, a liner 123 is hung loosely within the pipe 122, being supported by a flange 124 which rests on the upper end of the pipe 122. Within each tube 121 is a hollow cylindrical 30 scraping element 130, as shown in Figure 7. The upper and lower edges of this scraper may be of suitable sharpness as indicated in the figure. This scraper is mounted on the upper end of a rod 131, the mounting being preferably a trifle loose 35 so as to permit a slight wobbling of the axis of the scraper. To this end, each scraper element 130 may be provided with a pair of transverse plates 132 riveted or otherwise secured together. The ends of these plates are preferably welded as 40 at 133 into lateral holes in the scraper element 130. Central portions of the plates 132 are shaped to receive a shaft or pin 134 at the upper end of the rod 131, the shaft 134 being preferably threaded at its upper end to receive a pair of nuts 135 which may be spot-welded after being 45 screwed into place. This facilitates replacement of worn scraper elements 130. The supporting rods 131 are somewhat longer than the tubes 121 so that when the scraping elements 50 130 are near the upper ends of the tubes 121, the lower ends of the rods 131 project downwardly below the lower ends of the tubes 121 a sufficient distance to reach a movable supporting platform which may consist of a plate 136 mounted on a spider frame 137. As shown in Figure 7, each 55 supporting rod 131 may be provided with a threaded lower end portion 138 projecting through the supporting plate 136 and secured thereto as by a pair of nuts 140 which are preferably spot-welded after being set up in position. The spider frame 137, as shown in Figure 6, may comprise a suitable number of radial arms, four such arms being shown, projecting from a central hub 141. Through this hub projects the 60 upper end portion of a shaft 142, the hub resting 65

on a collar or flange 143 on this shaft. An extension 144 of this shaft projects upwardly through the central passage in the pipe 123, through the upper chamber 118 and out through the upper end of the shell 115, a suitable gland 145 being provided to prevent the escape of steam from the chamber 118 to the atmosphere. The highly concentrated liquor in #1 and #2 effects is of such a nature that it instantly becomes gummy upon exposure to air. Hence, in order to avoid excessive frictional resistance of the liquor-coated shaft 144 in the gland 145, I provide a small reservoir 146 surrounding the gland 145 and filled with water so that the shaft 144 as it slides upwardly through the gland 145 is 15 washed in the reservoir 146. Since the liquor is water-soluble, gumming of the surface of the shaft 144 is prevented. The outer ends of the arms on the spider frame 137 are preferably grooved as at 150 to slide on lateral guide rails 20 151 fixed on the inner walls of the shell 115 in the lower chamber 120. In order to maintain true alignment of the spider frame 137 and the scraper elements supported thereby, the shaft 142 is of sufficient length to project through a 25 slide bearing 152 set in the bottom of the shell 115. Projecting downwardly from the bearing 152 is a well 153 of sufficient length to receive the shaft 142 when the spider frame 137 is in its lowermost position as indicated in dotted lines 30 in Figure 4. A suitable by-pass 154 is provided between the lower end of the well 153 and the chamber 120 so as to permit displacement of the liquor in the well 153 when the shaft 142 descends thereinto. A perforated baffle plate 155 35 may be provided adjacent to the lower end of the shell 115, the discharge pipe 89 being connected to the bottom of the shell below this baffle plate. During the operation of the evaporator, the pipes 121 are heated by high pressure steam which 40 enters the chamber 119 through the steam supply pipe 30. This causes the liquor in the pipes 121 to boil. The formation of bubbles in the columns of liquor in the tubes 121 makes these columns of liquor lighter in weight. Hence, the 45 liquid pressure immediately below the lower ends of these tubes, due to the head of liquor in the large central pipe 123, is greater than the pressure of the columns of liquor in the tubes themselves. Thus the columns of liquor in the tubes 121 are forced upwardly, the liquor flowing into the upper chamber 118 and spilling back into the lower chamber 120 through the large central pipe 123. The rate of heat transmission through the walls of the tubes to the liquor therein is 50 limited, and depends partly on the velocity of the flow of liquor through the tubes, as explained in my Patent No. 1,582,066. There is a corresponding limit to the rate of formation of bubbles in the columns of liquor in the tubes 121. 55 The difference of pressure at the lower ends of these tubes, and hence the force propelling the columns of liquor upwardly through the tubes, depends upon the volume ratio of bubbles to liquor in these columns of liquor. The rate of formation of bubbles is limited and depends largely on the area of heated tube surface. Thus the ratio of bubbles to liquor in each column may be kept as high as possible by reducing to a 60 practical minimum the volume of liquor in each tube. To this end, I preferably make the supporting rods 131 of comparatively large diameter so as to fill a substantial portion of the space within each tube. This structure increases the 65 relative amount of foam in the tubes and thus 70

speeds up the flow of liquor upwardly through the tubes 121 and hence promotes the rate of heat transfer from the inner walls of the tubes 121 to the liquor flowing therethrough, the rate 5 of such heat transfer being a function of the speed of flow of the liquor through the tubes. In order to avoid excessive weight in the scraping apparatus as a whole, these supporting rods 10 may be made hollow as indicated in Figure 7.

10 The speeding up of the flow of liquor in the tubes 121 by displacing the liquor in the central or axis portion of the space within the tubes serves to wash from the scrapers 130 the solids which are scraped from the tube walls. It is evident 15 that the extent of displacement of the liquor in the central portion of the tubes depends not only on the diameter of the rods 131 but also on the position of the movable scraping apparatus including the scrapers 130, the rod 131 and the support 136, such displacement varying periodically from a minimum, when the scraping apparatus is in its lowermost position, to a maximum when the scraping apparatus is in its uppermost position. Thus the upward movement of this apparatus accelerates the flow of liquor in the tubes 121 until a maximum velocity of flow is reached 20 when the scrapers are near the upper ends of the tubes 121. This accelerated flow of liquor effectively prevents any accumulation of solids 25 on the scrapers or in the upper portion of the tubes.

Any suitable apparatus for reciprocating the scraping mechanism may be employed. In Figure 1 there is illustrated mechanism for this purpose. The upper ends of the shafts 144 are preferably attached to suitable cables 160 which carry counterweights (not shown) to take the dead weight load of the scrapers and their supporting members from the mechanism for moving these members. As shown, the upper portion 30 of each shaft 144 is screw-threaded for a considerable length as at 161, this threaded portion being in threaded engagement with a nut 162 on which is mounted a worm gear 163 meshing with a worm 164 which may be driven by a suitable motor 165. Since the shaft 144 is prevented from rotation on its axis by the guides 151 and a key 35 inserted in the bearing in engagement with a keyway in the part of the shaft having a screw thread, rotation of the worm gear 163 will cause the shaft 144 to rise or fall according to the direction of rotation of the worm gear. Suitable automatic controls (not shown) are provided to 40 reverse the motion of each shaft 144 when it reaches either end of its stroke, such reversing means being well known in the art. For the lubrication of the threaded portion 161 of the shaft, I may provide an oil reservoir 170 mounted at the lower end of the threaded portion. Oil which 45 collects in this reservoir may be pumped by a small motor 171 through a flexible hose 172 to be discharged through a suitable nozzle 173 on the threaded end portion 161 immediately above the nut 162. The motor 165 may be operated at any 50 desired rate to ensure sufficiently frequent scraping of the inner surfaces of the tubes 121 to prevent the deposit of anhydrite scale on the inner surfaces thereof.

Figure 9 of the drawings illustrates in longitudinal section one of the horizontal effects employed in the evaporator. As shown, each such effect consists of a boiler shell 180 within which are mounted a pair of tube sheets 181, 182. A number of horizontal tubes 183 extend from the tube sheet 181 to the tube sheet 182 and open

into end chambers 184 and 185 within the shell 180. In large sized effects, the tubes 183 may be of considerable length so that I may provide one or more intermediate tube sheets 186 to support such tubes. These sheets may divide the intermediate steam chamber 187 into two or more compartments, such compartments being in communication with each other as by an opening 188 formed by cutting away the lower portion of each intermediate tube sheet 186. This permits 10 free flow of condensate from the various portions of the steam chamber into the well 189. Separate steam inlets 190 and 191 are preferably provided for the several compartments of the steam chamber so as to ensure a sufficient supply 15 of steam to all the exterior surfaces of the tubes 183. The liquor to be evaporated is supplied through one or more pipes 81 from a supply pump 80, which enter the supply chamber 184. The volume rate of delivery of weak liquor to the 20 evaporator is subject to considerable variation at times owing to conditions of operation in the pulp mill. There is a practical limit to the size of a nozzle of the type described in my Patent No. 1,582,066 for effective breaking up of the jet 25 of liquor supplied at various pressures, into a uniformly distributed spray for projection against the tube sheet 181 and the open ends of the tubes 183 projecting therethrough. Hence, in order to provide ample supply capacity for each effect, I 30 may employ a battery of spray nozzles 192, each such nozzle being of sufficiently small size to be effective in uniformly distributing the liquor flowing therethrough regardless of the pressure at which the liquor is supplied. The lower nozzles 35 are preferably of somewhat smaller diameter than the larger nozzles to compensate for differences in liquid pressure due to liquid head. By this means, a substantially uniform distribution of liquor over the face of the tube sheet 181 may be 40 obtained. It is sometimes necessary to operate the evaporator under radically different conditions of liquor supply. In order to take care of this problem, I may provide two batteries of nozzles as indicated in Figure 10. Figure 11 illustrates one such battery of nozzles, these nozzles being mounted on a manifold 193 of piping so as to support the nozzles in a symmetrical array for uniform distribution of liquor therefrom. In addition to the manifold 193 I may provide a second manifold 194, each manifold being controlled by a separate gate valve so that either one may be shut off entirely when not needed. By this means, the supply rate of liquor to any horizontal effect may be radically changed without necessitating access to the interior of the chamber 184 for the purpose of changing nozzles.

As described and illustrated in my patents hereinbefore referred to, a series of gill flanges 195 may be mounted on the face of the tube sheet 60 181 to assist in the uniform distribution of liquor projected against the tube sheet into the several horizontal rows of tubes, one such flange 195 being mounted beneath the orifices of each such horizontal row of tubes. For the efficient operation of the effects, it is necessary that the entire inner surfaces of all the tubes 183 be constantly wetted by liquor so that there will be an uninterrupted transfer of heat from all the heating surfaces to the liquor. When the supply stream 70 of liquor to an effect has been insufficient to keep the tubes 183 sufficiently filled with liquor to wet the entire interior surfaces thereof, it has been my previous practice to recirculate a portion of liquor discharged from such effect to the sup- 75

ply end of the same effect so as to maintain a sufficient volume of liquor entering thereto. As a result of this, however, the incoming liquor is at a higher concentration than the liquor initially supplied to such effect. This means a change in the boiling point of the liquor due to its higher concentration, and consequent loss of efficiency in the operation of the evaporator as a whole. To avoid the necessity of re-circulation of liquor through any of the horizontal effects, I provide, according to the present invention, other means for maintaining a sufficient supply of liquor in the tubes 183. To this end, I provide dams or barriers outside of the discharge ends of the tubes 183, these dams being preferably in the form of transverse plates secured to the tube sheet 182, the lips of these plates being approximately on a level with the central axes of the tubes in the corresponding horizontal row, as illustrated in Figures 14 and 15. These dams may be of any suitable shape, having a vertically extending wall 186 as shown in Figure 14, or an outwardly sloping wall 187 as shown in Figure 15. Dams of this kind back up sufficient liquor in the tubes 183 to ensure thorough wetting of all the interior surfaces of these tubes by the boiling and resultant foaming of the liquor therein.

In the ordinary operation of a horizontal effect of the type illustrated in Figure 9, the liquor in the tubes 183 rushes through the tubes with considerable velocity owing to the ebullition of the liquor therein and the difference of pressures in the end chambers of the effect. This velocity of the liquor within the tubes makes for efficient heat transfer from the inner tube surfaces to the liquor itself. One result of this velocity and foaming of the liquor is the delivery of a mixture of finely divided liquor and steam in large quantities into the chamber 185. This chamber serves as a separation chamber in which the steam is separated from the liquor, the steam being discharged upwardly through the connection 33 to the section of the steam line 32 through which it is delivered into the steam chamber of the next adjacent effect. Since this steam is condensed in the next effect in the course of heating and boiling the liquor in the tubes of the next effect, the condensate therefrom is delivered into the well 48 of the next effect and follows the course of the condensate through the several wells 48 to the weir 44 and the trap 45, as hereinbefore described. It is evident that if the separation of steam from liquor in the chamber 185 of any effect is not complete, the entrained liquor which is carried over by the steam into the next effect will be found in the condensate which eventually finds its way to the weir 44 and trap 45. Since a primary object of the evaporator is to recover the chemicals present in the weak liquor, it is desirable that none of the chemical materials be lost in this manner by escape of the condensate. Hence it is important that the separation of steam from liquor in the chamber 185 be as complete as possible. This separation is made difficult by the delivery of large quantities of foam and finely divided liquor from the tubes 183, and by the high velocities of the streams of steam flowing from the effects, particularly in the case of the low pressure effects where the volume of the steam is greatly magnified by the low pressures. In order to obtain an efficient separation of steam from liquor, a baffle plate 201 is mounted in the chamber 185 sloping downwardly away from the tube sheet 182. Considerable clearance is allowed be-

tween the lower edge of this plate and the bottom of the shell 180 so as to provide an ample passage for the steam to escape to the portion of the chamber beyond the baffle plate 201 and thence upwardly through the outlet 200. According to the present invention, I form the lower edge 202 of the baffle plate 201 in such a manner as to slope downwardly from a high central point. Along the greater portion of this edge on the side of the baffle plate toward the tube sheet 182, I mount a suitable gutter 203. This gutter is of sufficient size to accommodate the liquor which strikes the face of the plate 201 and runs down thereon toward the lower edge. The gutter thus prevents the formation of a curtain of liquor 15 dripping from the lower edge 202 of the baffle plate 201 and thus avoids a tendency on the part of the stream of steam flowing through the opening beneath the baffle plate to sweep such drippings of liquor upwardly through the chamber 20 185 and the outlet 200 into the steam chamber of the next effect. The gutter 203 leads such liquor laterally to the sides of the shell 180 so that it flows directly into the well 48.

As shown in Figure 16, I may provide within 25 the steam chamber 187 of each horizontal effect a longitudinally extending baffle plate 205 which projects downwardly from the upper portion of the shell 180 to a point well above the lower portion of the shell so as to provide ample clearance 30 between the lower edge of the baffle and the inner surface of the shell. This baffle plate is preferably mounted off to one side a substantial distance from the median plane of the effect. As shown in Figure 16, it is placed to the right of 35 the median plane. The air pipe connection 61 from the previous effect enters the upper part of the steam chamber on one side of the baffle plate 205, the air discharge pipe 62 being connected to the steam chamber on the opposite 40 side of the plate 205. As shown, the baffle plate may be adjacent to the orifice of the discharge pipe 62. During the operation of the evaporator, there is a constant suction maintained on the air line so as to create a flow through the connecting pipes 61 and 62 from one effect to the other along the line. Any air or other gases which may be present in any of the effects is projected downwardly from the pipe 61 into the steam chamber 187 together with considerable 50 entrained steam. The suction in the pipe 62 draws such air over to the adjacent side of the steam chamber so that the air is more efficiently removed from the steam chamber than it can be when the inrush of steam through the 55 inlets 190 to be condensed on the tubes 183 tends to sweep such air or gases downwardly to the bottom of the effect. The baffle plate 205 thus results in a more efficient removal of adventitious air from the steam chambers of the several effects, with a consequent improvement in the efficiency of the evaporator as a whole.

As hereinbefore stated, a primary object of the evaporator is to recover the chemicals in the weak liquor so that it is desirable that none of these 65 chemicals be lost with the condensate from the steam supplied to the various effects. In the average mill, the operators work more by rule of thumb than according to actual knowledge of what is going on inside of the apparatus. Hence 70 it is desirable that means be provided for checking up on the functioning of the evaporator to see that such losses of liquor containing valuable chemicals are not occurring. For example, an operator may be instructed to carry 28 inches of 75

vacuum in the condenser. If the barometer reads 29 inches of atmospheric pressure, that will mean that if a 28-inch vacuum is maintained in the condenser, the evaporator will be operating under a pressure of 1-inch absolute; whereas if the barometer reads 30 inches of mercury, the evaporator will be operating under an absolute pressure of 2 inches. The volume of steam at 1-inch absolute is far greater than volume of the same quantity of steam at 2-inches absolute pressure. Since a large volume of steam means a correspondingly large velocity of flow of steam in the streams issuing from the separation chambers 185 of the several effects, and particularly in the case of the low pressure effects, excessive vacuum in the condenser may result in the entrainment of more or less liquor in the steam. Such a possibility is avoided as far as is practical by designing the apparatus with large steam delivery pipes 33 which increase in size for the effects operating at lower pressures, as indicated in Figure 1, so as to reduce the steam velocities by large cross sectional areas of the pipes which carry the steam from the low pressure effects. In any actual installation, however, there are limits to the steam velocities which cannot be exceeded without carrying more or less liquor into the condensate. Hence, in order to keep track of the completeness of separation of steam from liquor, I provide weirs 44 and 52 constructed in such a manner that they not only indicate the rate of delivery of condensate from the evaporator but also provide a visible indication of the purity of the condensate. The presence of even a small percentage of liquor in the condensate colors it so that it can easily be detected. To this end, I may employ weirs such as that illustrated in Figure 24. As shown, this weir consists of a container 210 having a transverse wall 211 forming an inlet chamber 212. The wall 211 is suitably notched as at 213 to permit a flow of liquid from the chamber 212 to the adjoining chamber 214. The level of the liquid in the chamber 212 is a function of the rate of supply of the liquid to the chamber, this rate being indicated by a suitable scale 215 opposite a sight glass 216 through which the level may be observed. The condensate is supplied to the chamber 212 through a suitable pipe 217. In the chamber 214 is a dam 220, the crest of which is lower than the bottom of the notch 213. The liquid flowing over the crest of the dam 220 escapes through a discharge pipe 221. A sight glass 222 is mounted in an inclined position outside of the container 210, the lower end of the glass communicating with the pool of liquid behind the dam 220, the upper end of the glass opening into the chamber 214 in front of the dam 220 and below its crest so that there is a constant flow of a portion of the pool behind the dam 220 through the sight glass 222. This glass if properly illuminated, indicates the purity of the condensate delivered to the weir, the presence of any appreciable percentage of liquor visibly discoloring the condensate flowing therethrough. Thus if any liquor is being lost by entrainment in one or more streams of steam from the effects, its presence is readily observable, and the evaporator can be accordingly regulated to avoid such escape of liquor.

The heat exchanger 82 by which a hot weak liquor is made to give up a portion of its heat to warm the cold liquor passing from #10 effect to #4 effect is preferably of considerable length in order to transfer as much heat as possible from the weak liquor to the partially concentrated

liquor. In order to avoid danger of clogging in elbows or bends, such heat exchanger is preferably constructed in a single extended length, as indicated in Figure 1, the actual length of the exchanger employed in the apparatus illustrated being approximately sixty feet. Since it is impracticable to employ tubes of such length, I prefer to build the heat exchanger in sections as indicated in Figures 18 and 19. As shown, the heat exchanger may comprise three sections, but it is apparent that a greater or lesser number of sections may be employed in like manner. The heat exchanger, as shown, consists of two end sections with or without one or more intermediate sections. Each end section consists of a shell 230 with an end plate 231 and a tube sheet 232 adjacent thereto forming an end chamber 233. At the opposite end of this section is a second tube sheet 234. A number of tubes 235 extend between and open through the tube sheets 232 and 234. The outer face of the tube sheet 234 is preferably ground or otherwise made truly plane so as to abut a similar tube sheet forming an end of the adjacent section of the heat exchanger. If intermediate sections are employed, one such intermediate section being shown in Figure 18, both ends of such intermediate section consist of tube sheets 234 adapted to abut the terminal tube sheets of the adjoining end sections. Each of the tube sheets 234 is formed with an identical pattern of perforations, such as that shown in Figure 19, so that the perforations of pairs of abutting tube sheets 234 register with each other. In addition to the perforations to receive the tubes 235, the tube sheets 234 are additionally perforated between the tubes 235 as at 236. Since the combined areas of the openings 236 are necessarily considerably smaller than the cross sectional area of the spaces between the tubes 235 within the shell 230, I preferably provide additional apertures 237 of larger size through the tube sheets 234, as shown in Figure 18. In order to provide such apertures, one or more of the tubes 235 must be omitted. The omission of these tubes moreover serves the purpose of providing distribution chambers 240 adjacent to the orifices of the supply pipes 81 so that the entrance of liquor into the inter-tubular space within the shell 230 is not impeded by the presence of pipes 235 directly in front of such orifices. For the efficient functioning of the heat exchanger, it is necessary that the liquor flowing through the inter-tubular spaces be distributed in these spaces as uniformly as possible so as to maintain as uniform a temperature gradient as possible from one end of the exchanger to the other. Since the omission of one or more tubes 235 would provide easy channels for the flow of liquor from the chambers 240 to the openings 237 without touching the tubes, which would reduce the effectiveness of the exchanger, provision is made to close off such channels by the location of volume-occupying members 241 therein. These members may be in the form of pipes of suitable size, closed at the ends, and mounted on the walls of the shell 230 in such a manner as to fill most of the space between the chambers 240 and the openings 237, clearance being allowed adjacent to the latter, as at 242, to facilitate the flow of liquor to and from the inter-tubular spaces through the openings 237.

The pumping of liquor from one effect to another has heretofore been attended by difficulties owing to the fact that the unevaporated liquor leaves each effect at a temperature very close to

its boiling point so that if any appreciable heat is added thereto, steam tends to form therein. Pumps are necessary for the proper transfer of liquor from one effect to another. No pump is perfectly efficient mechanically, that is, in any pump there is necessarily a generation of heat due to friction such as between the pump parts and the liquor. The heat thus generated results in troublesome steam in the pump which seriously affects the operation thereof. It has been found as a practical matter that the centrifugal type of pump is best suited for the transfer of liquor from one effect to another. The generation of heat within a pump of this kind tends to result in the formation of a steam pocket within the casing of the pump which holds the liquor away from the paddles and thus interferes with the pumping action. It would be undesirable and inefficient to attempt to chill the entire liquor stream supplied to these pumps sufficiently to prevent such formation of steam. Various expedients, such as mounting the pumps in deep pits so that the pumps operate at least thirty feet below the bottom of the effects, have been tried with more or less success, such expedients being in general open to practical objections since the pumps must be readily accessible if they are to receive necessary care and attention. According to the present invention, I provide simple but effective means for preventing objectionable formation of steam pockets in the pumps by supplying thereto cold liquor along the surface of the shaft which carries the paddle wheel. By introducing a cold liquid in this manner at the center of the pump casing, a relatively small quantity is amply sufficient to condense the steam in the pump casing or to prevent the formation of steam in objectionable amounts therein, without unduly chilling the stream of liquor as a whole. Furthermore, by employing cold liquor from #10 effect, there is no loss of efficiency in evaporation since the water contained in this partially concentrated liquor must eventually be evaporated anyway. As shown in Figure 1, I provide a branch pipe line 260 from the discharge end of the pump 86 which receives liquor from #10 effect. The pipe 260 extends along the entire apparatus, branch pipes 251 leading off from this pipe at convenient points to carry cold liquor to the several pumps 80. As shown in Figure 20, the liquor supply pipe on the suction side of the pump enters the pump casing through one side thereof, the paddle within the pump being mounted on a shaft 252 which enters the opposite side of casing and is preferably aligned with the supply orifice. A suitable motor 253 or other convenient means of driving the shaft 252 is connected thereto. According to the invention, the shaft 252 extends through a hollow boss 254 which projects laterally from and may be integral with the side of the pump casing 255. The boss 254 has an interior bore of sufficient diameter to form an interior shoulder 256 with the casing wall 255 but to leave a considerable clearance 257 between the shaft and the wall 255. Within the bore of the boss 254, I insert a gland member 260, this member being adapted to engage with its inner end against the shoulder 256. The member 260 is in the general shape of a hollow cylinder having a central bore adapted to receive the shaft 252. The central portion of the bore is relieved or enlarged as at 261 to form a chamber around a portion of the shaft 252. The inner end of the bore is also slightly larger in diameter than the shaft 252 so as to provide a definite clearance 262 about the

shaft. This clearance is carefully regulated so as to provide a passage of definite cross sectional area between the chamber 261 and the interior of the pump casing. The branch pipe 251 communicates with the chamber 261 by suitable passages in the member 260. To this end, the member 260 may be provided with an exterior peripheral groove 263 communicating with the chamber 261 through one or more apertures 264. Between the outer end of the member 260 and gland 265 is a suitable packing 266 to prevent the escape of liquid from the pump casing along the shaft 252. The cold liquor supplied from #10 effect enters in a small stream through the pipe 251 and the passages in the member 260, including the clearance space 262 about the shaft, so that the cold liquor reaches the center of the pump casing along the surface of the shaft, precisely where it is most effective. This continuous trickle of cold liquor into the center of the pump effectively prevents the formation of objectionable steam pockets therein. In order to avoid the necessity of control valves for regulating the size of the streams of cold liquor into the pump casing, the use of valves being objectionable where avoidable, I employ the members 260 for such regulation. If a larger or smaller rate of supply of cold liquor to any pump is desired, the member 260 may be quickly and easily replaced by a similar member having a larger or smaller clearance 262.

One of the problems of pulp mill practice arises from the very considerable loss of heat energy due to the escape of large quantities of steam when a digester is discharged into the blow pit. According to the present invention, I avoid a great deal of such loss by utilizing blow-pit steam and any other steam available in the mill which would otherwise be wasted, by sending such steam through a suitable pipe 280 into a condenser 281 of suitable size and construction. The steam supplied to this condenser condenses on the surface of a number of tubes therein which are full of weak liquor circulated from the storage vat 10. As shown, a supply pipe 282 may lead from the bottom of the vat to the condenser 281, a return pipe 283 leading from the condenser back to the vat 10 at a point considerably above the bottom of the vat, but preferably below the average working level of the liquor stored in the vat. The heat given up by the condensation of the steam in the condenser 281 serves to raise the temperature of the liquor within the tubes of the condenser. Whether or not the liquor is thereby boiled, its specific gravity will be lowered so that there will be a natural gravitational circulation of liquor through the condenser from the bottom of the vat to the point of entry of the return pipe 283. If desired, a suitable pump (not shown) may be employed to assist circulation. Thus the steam which would otherwise be wasted in the mill is employed to heat the liquor in the vat before it is supplied to the evaporator. It is obvious that the hotter the liquor is when it is supplied to the evaporator, the more efficiently the evaporator will operate, since less steam in the evaporator will be required to warm up the liquor to its boiling point than if the liquor is supplied cold. The condensate from the condenser 281 may be discharged through a suitable steam trap 285.

I claim:

1. In the art of evaporation, a process which comprises flowing liquor over a heated surface, intermittently scraping said surface in the direction 75

- of said flow, and continuously increasing the velocity of flow over said surface during each period of scraping movement in said direction.
2. In the art of evaporation, a process which comprises flowing liquor over a heated surface, periodically moving a scraping element across said surface at substantially constant speed, in the direction of flow, and continually increasing the velocity of flow over said surface during each period of scraping movement in said direction.
3. In the art of evaporation, a process which comprises flowing liquor over a heated surface, intermittently scraping said surface during said flow with a movement in the direction of flow and slower than the flow itself, and continuously increasing the velocity of flow during each period of scraping movement in said direction.
4. In the art of evaporation, a process which comprises flowing liquor over a heated surface, scraping said surface during said flow by alternate movements with and against said flow, the scraping movement in the direction of flow being at a substantially constant speed and slower than the flow itself, and continuously increasing the velocity of flow during each period of scraping motion in the direction of flow.
5. In the art of evaporation, a process which comprises heating a tube externally, flowing liquor through said tube, scraping the inner surface of said tube from end to end alternately with and against the flow and progressively displacing liquor from the central portion of the space within the tube during the scraping movement in the direction of flow.
35. 6. A process of evaporation, which comprises delivering liquor into an externally heated horizontal tube and maintaining the quantity of liquor in said tube above a predetermined minimum by backing up a portion of the liquor in the tube from a point beyond the discharge end thereof, whereby the interior of said tube is unobstructed.
7. In the art of multiple-effect evaporation, the method of facilitating the centrifugal pumping of liquor at its boiling point from one effect to another, which comprises injecting into the centrifugal chamber a small stream of cold liquor of higher concentration.
8. In the art of multiple-effect evaporation, a process which comprises supplying weak liquor initially to an intermediate effect, pumping the liquor from each effect to the next effect at a temperature near its boiling point, concentrating said liquor by steps in successively cooler effects to the coldest effect, then through the remaining effects at successively higher temperatures to the hottest effect, and introducing a portion of the partially concentrated liquor from the coldest effect into the pumping chambers of the several liquor pumps to counteract steam-forming tendencies therein.
60. 9. A multiple-effect evaporator comprising a series of combined evaporating and condensing units adapted to operate at descending temperatures and pressures, each said effect having a supply port for the introduction of liquor to be concentrated therein, a heat exchanger, a supply line for initially hot weak liquor leading through said exchanger to the supply port of an intermediate unit, connections between said intermediate unit and the cooler units for conducting liquor through said cooler units in series for concentration therein, a pipe line for liquor extending from the coldest unit through said heat exchanger to the supply port of the unit next hotter than said intermediate unit, connections for conducting liquor from said next hotter unit through the remaining

units in progressively hotter sequence, pumps in said liquor connections, and means for conducting small streams of liquor from the coldest unit to the pumping chambers of the several pumps to counteract steam forming tendencies therein.

5. 10. In an evaporator unit of the vertical type, a boiler shell, a pair of horizontal tube sheets therein, vertical tubes opening through said sheets, a frame vertically reciprocable in said shell below the lower tube sheet, stems mounted on said frame projecting upwardly into the several tubes, a scraper element at the upper end of each said stem, a central guide shaft projecting downwardly from said frame, a guide bearing fixed in the lower end of said shell, a fluid-tight well extending down 10 from said bearing to receive said shaft, and means for reciprocating said frame and scrapers.

11. In an evaporator unit, a vertical tube for liquor, a hollow scraper reciprocable in said tube, a hollow stem projecting into said tube and carrying said scraper, said stem having a cross-sectional area equal to a substantial fraction of that of the interior of the tube, and means for reciprocating said scraper in said tube from end to end thereof during the operation of said unit.

20. 12. In an evaporator unit, a vertical tube for liquor, a hollow cylindrical scraper loosely fitted in said tube and reciprocable therein, a stem carrying said scraper at one end thereof, said stem being hollow for most of its length and having a 30 cross-sectional area equal to a substantial fraction of that of the interior of the tube, and means for reciprocating said scraper in said tube from end to end thereof.

25. 13. In an evaporator unit of the vertical type including a boiler shell and tubes therein for liquor, scraping mechanism for the tubes reciprocable in said shell, means for reciprocating said mechanism including a rod projecting through the top of said shell, a gland on said shell for said rod, and 40 means for maintaining a pool of liquid about said gland and adjacent portion of the rod projecting upwardly therefrom.

14. In an evaporator unit having a tube sheet and a set of horizontal tubes opening through said sheet, a battery of spray nozzles directed toward said sheet and open tube ends and laterally spaced from each other to spray liquor substantially uniformly over the face of said sheet, an auxiliary battery of nozzles spaced between the 50 first said nozzles, supply pipe lines to said batteries, and valves in said supply lines.

15. An evaporator unit comprising a pair of tube sheets, a plurality of rows of substantially horizontal tubes extending between and opening 55 through said sheets, means for supporting said sheets for the application of heat to the exterior surfaces of said tubes, means opposite one of said sheets for distributing liquor in the form of spray thereagainst and into said tubes, and means 60 for maintaining the liquor in each tube above a minimum level, said last-named means including means adjacent to the receiving ends of the tubes for receiving the spray not entering the tubes directly and delivering it into the tubes, and dam- 65 ing means beyond the discharge ends of the tubes.

16. In a multiple-effect evaporator, a plurality of effects each having a steam chamber therein, and pipes extending through said chamber to 70 conduct liquor for evaporation by condensation of steam on the exterior surfaces of said pipes, a well under each steam chamber to receive condensate therefrom, and a connecting pipe from the bottom of said well to the steam chamber of 75

the next successive effect, said pipe having a portion at a level sufficiently below said effect to be kept full of condensate by the liquid head therein opposed to the difference of pressures in the steam chambers of said effects with which said pipe communicates.

17. In a multiple-effect evaporator, a plurality of effects in series, a pipe line for transferring liquor at or near its boiling point from one effect to another, a pump in said pipe line, and means for introducing a stream of cold liquor from one of said effects into the pumping chamber of said pump during the operation thereof to prevent the formation of steam therein.

18. In a multiple-effect evaporator, a plurality of effects in series, a pipe line for transferring liquor at or near its boiling point from one effect to another, a pump in said pipe line, and means for introducing into the pumping chamber of said pump during the operation thereof a stream of liquor from the coldest of said effects.

19. In a multiple-effect evaporator consisting of a series of effects arranged in descending order of temperatures and pressures therein, means for introducing weak liquor into an intermediate effect, pipe connections between successive effects for conducting unevaporated liquor from said intermediate effect to successively colder effects and from the coldest effect to the remaining effects in sequence of ascending temperatures, a pump

in each said pipe connection, and means for diverting a sufficient portion of the partially concentrated liquor from the coldest effect to the pumping chambers of certain of said pumps to prevent said pumps from becoming steam-bound. 5

20. In a multiple-effect evaporator, a series of effects, pipe lines from one effect to another arranged to conduct the liquor from effect to effect in a predetermined order such that the liquor leaving the coldest effect is partially concentrated, a centrifugal pump in each said pipe line, means including a rotatable shaft for driving said pump, fluid connections from the pipe line leaving the coldest effect to certain of said pumps, and means for introducing cold liquor through 15 each said connection into the pumping chamber of the corresponding pump along the surface of its drive shaft.

21. In a multiple-effect evaporator, a condenser, a steam pipe leading from the coldest effect to said condenser, a drain pipe from said condenser to lead off condensate therefrom, a weir connected in said drain pipe, and means associated with said weir for indicating the rate of flow 20 of condensate therethrough and transparent means through which a portion of the stream of condensate is by-passed to facilitate detection of color changes therein.
